Attest

United States Patent Office.

JOHN STEPHEN, OF WOMELSDORF, PENNSYLVANIA.

Letters Patent No. 67,602, dated August 6, 1867.

IMPROVEMENT IN LADIES' THIMBLES.

The Schedule referred to in these Letters Patent and making part of the same.

TO ALL WHOM IT MAY CONCERN:

Be it known that I, JOHN STEPHEN, of Womelsdorf, in the county of Berks, and in the State of Pennsylvania, have invented certain new and useful Improvements in "Thimbles;" and do hereby declare that the following is a full, clear, and exact description thereof, reference being had to the accompanying drawings, and to the letters of reference marked thereon. In the annexed drawings making part of this specification—

A represents a thimble, which is intended to be used upon the finger for sewing. The outer end of this thimble is provided with numerous indentations, as is usually the case. These indentations extend down on the sides of the thimble about two-thirds of its length, and from where they leave off to the ring *e*, at the mouth, is a series of grooves, *x x*, which radiate from the ring toward the end of the thimble. The ring *e* is provided with a groove at the end of the grooves *x x*, as seen. The object of the grooves in the sides of the thimble is to catch the end of the needle in case it slips from the indentations, and guide it into the groove of the ring *e*, where it is stopped and prevented from doing injury to the finger of the wearer.

Having thus fully described my invention, what I claim as new, and desire to secure by Letters Patent, is—

A thimble provided with the radiating grooves *x x*, and at their ends with the groove in the ring or flange *e*, substantially as and for the purpose herein specified.

In testimony that I claim the foregoing I have hereunto set my hand this 21st day of March, 1867.

JNO. STEPHEN.
